UNITED STATES PATENT OFFICE

CHARLES H. JARVIS, OF BATTLE CREEK, MICHIGAN, ASSIGNEE TO UNITED STEEL & WIRE COMPANY, OF BATTLE CREEK, MICHIGAN

SHELVING

Application filed May 16, 1930. Serial No. 453,043.

The main objects of this invention are:

First, to provide a metal shelving which may be easily and quickly set up by unskilled workmen and when set up is strong and rigid.

Second, to provide a metal shelving which may be set up without the use of bolts or fastenings of like character and one in which there are no exposed fastenings in the assembled structure.

Third, to provide a metal shelving having these advantages which is very attractive in appearance.

Objects pertaining to details and economies of my invention will definitely appear from the description to follow. The invention is defined in the claims.

A structure which embodies the features of my invention is clearly illustrated in the accompanying drawings in which:

Fig. 1 is a fragmentary front elevation of shelving embodying the features of my invention.

Fig. 2 is a fragmentary plan view.

Fig. 3 is a detail vertical section from front to rear on line 3—3 of Fig. 1.

Fig. 4 is an enlarged detail vertical section on line 4—4 of Fig. 3 showing the mounting for the shelves and the relation thereof to the uprights.

Fig. 5 is a fragmentary section on line 5—5 of Fig. 1 showing details of the bracing.

Fig. 6 is a detail section of shelf on line 6—6 of Fig. 3 showing further details of the shelf mounting.

Fig. 7 is a fragmentary view in section on line 7—7 of Figs. 1 and 8 showing details of the connections for the pairs of uprights and the support for the bottom panels.

Fig. 8 is a fragmentary section on line 8—8 of Fig. 7.

Fig. 9 is a perspective view of one of the adjustable shelf supports.

Fig. 10 is a fragmentary elevation showing a modified form of shelf adapted for the supporting of caddies and the like in an inclined position.

Fig. 11 is a detail view partially in section on line 11—11 of Fig. 10.

Fig. 12 is a perspective view of one of the corner shelves.

Fig. 13 is a fragmentary vertical section on a line corresponding to line 13—13 of Fig. 15, showing details of the mounting for 55 the rear end of the corner shelf.

Fig. 14 is a fragmentary section on line 14—14 of Fig. 13 showing further details of the corner shelf mounting and prior to the locking of the shelf to its support.

Fig. 15 is a fragmentary section on line 15—15 of Fig. 13.

Fig. 16 is a fragmentary section on line 16—16 of Figs. 1 and 17 showing details of the support for the corner bottom panel.

Fig. 17 is a fragmentary section on line 17—17 of Fig. 16.

I have illustrated my invention in the accompanying drawings as I have embodied the same for store shelving. The structure 70 illustrated comprises pairs of front and rear uprights 1 and 2 connected at the tops and bottoms of the sheet metal cross pieces 3. These uprights are formed of T iron disposed with the central arms 4 thereof projecting inwardly. The cross members 3 are preferably secured to the inwardly projecting arms of the uprights by spot welding as indicated at 5.

The upper cross member is not illustrated 80 in detail but it will be understood that it is the same as the bottom cross member shown in detail in Figs. 7 and 8.

A pair of the connected front and rear uprights are suitably spaced to receive the shelves 6 between their inwardly projecting arm. The rear uprights of the pair are braced by the crossed braces 7 which are pivotally connected at their crossing point as at 8. The ends of these braces terminate in rearwardly offset lugs 9 engageable with slots 10 in the uprights. The offsets in the braces provide shoulders engaging the slots to receive the thrust. The braces may be sprung sufficiently to permit their engagement and they are engaged before the shelves are put in place, the shelves coacting with the braces to rigidly support the uprights.

The inwardly projecting arms of the uprights have a vertically spaced series of holes 100

11 therein adapted to receive the W-shaped shelf supports 12 which are arranged through selected holes according to the desired spacing of the shelves, providing a pair 5 of upwardly facing shelf supporting hooks 13 connected by a saddle portion which engages the uprights.

The shelves 6 have downturned flanges 15 at their ends and flanges 16 at their front 10 and rear edges, the lower edges of the flanges 16 being turned inwardly at 17. These flanges render the shelves rigid, although made of relatively light material, add to the appearance of the shelves, and, also, when 15 provided with the inturned flanges 17, present a rounded or smooth edge, minimizing the likelihood of injury in placing goods on and removing them from the shelves.

The end flanges 15 are engaged in the hook 20 portions 13 of the supports or hangers 12. These flanges have portions struck inwardly at the ends thereof to provide hanger engaging lugs 18 so that the shelves serve as tie members preventing the spreading of the upper 25 rights as well as tie members for the adjacent uprights.

The bottom panel members 19 are also preferably formed of sheet metal. To removably support these panels 19 I secure the angled 30 members 20 to the inwardly projecting arms of the front uprights, preferably by spot welding as indicated at 21, Fig. 8. The arms 22 of these members 20 are spaced from the adjacent front arm of the upright to receive 35 the ends of the member 19. The member 19 has an inturned flange 23 at its upper edge with which the inturned portion 17 of the flange of the bottom shelf abuts, thereby providing a closed joint between these parts and containing sharp edges.

When it is desired to provide the shelving with a set of corner shelves, I provide an upright 24 having a series of holes 25 therein adapted to receive the shelf hangers 12. The 45 corner shelves 26 are of triangular shape having rounded front edges provided with downturned flanges 27. Their side edges have downturned flanges 28 which are notched at 29 and 30 to engage the hangers.

50 Bendable lugs 31 are formed on the edges of the notches 30 and adapted, after the shelf is engaged with the hanger, to be bent under the same as shown in Fig. 13, thereby preventing the tilting of the shelves.

55 These corner shelves, at least the bottom shelf, are provided with vertical slots 32 adjacent its front flange to receive the curved bottom panel member 33, which has inturned flanges 34 at its ends. The panel 33 is by this 60 means effectively locked and supported in position by the bottom shelf.

With the parts thus formed, the entire structure may be quickly and easily set up by an unskilled person without the aid of tools, at least, tools other than a hammer or

70 mallet which might be employed for driving the parts into position. There are no exposed bolts or other fastenings, and the structure may be readily knocked down should occasion require to be set up in another position. At the same time, the structure is strong and rigid and capable of carrying heavy loads.

75 In the modification shown in Figs. 10 and 11, the shelves 35 are trough-shaped, designed for supporting caddies and the like in an inclined position. These shelves are secured to cross pieces 36 having out-turned flanges 37 engageable with the hangers.

80 I have not attempted to illustrate other adaptations and modifications of my improvements as it is believed that this disclosure will enable those skilled in the art to embody or adapt the same as may be desired.

85 Having thus described my invention what I claim as new and desire to secure by Letters Patent is:

1. In a structure of the class described, the 90 combination of front and rear T iron uprights disposed with their central arms inwardly and having a series of vertically spaced holes therein, the front and rear uprights being connected in pairs by sheet metal top and bottom members disposed vertically against the sides of and secured to the inwardly projecting arms of the uprights, the rear uprights having holes in their laterally projecting arms adjacent the top 95 and bottom thereof, crossed braces pivotally connected at their crossing points and having offset lugs engaging said holes in the lateral arms of adjacent rear uprights, W-shaped shelf hangers having their central loops engaged in holes in said inwardly projecting arms of said uprights, thereby presenting upwardly facing shelf engaging hooks, and shelves having end flanges engaged in said hanger hooks.

100 2. In a structure of the class described, the 110 combination of front and rear T iron uprights disposed with their central arms inwardly and having a series of vertically spaced holes therein, the rear uprights having holes in their laterally projecting arms adjacent the top and bottom thereof, crossed braces pivotally connected at their crossing points and having offset lugs engaging said 115 holes in the lateral arms of adjacent rear uprights, shelf hangers engaged in holes in said inwardly projecting arms of said uprights, and shelves having end flanges engaged in said hangers.

120 3. In a structure of the class described, the 125 combination of front and rear T iron uprights disposed with their central arms inwardly and having a series of vertically spaced holes therein, shelf hangers engaged in holes in said inwardly-projecting arms of said uprights, and shelves having end flanges 130

- engaged in said hangers, the end flanges of said shelves having lugs struck inwardly therefrom engaging said hangers so that the shelves constitute tie members for the up-
rights.
4. In a structure of the class described, the combination of front and rear T iron uprights disposed with their central arms inwardly and having a series of vertically spaced holes therein, W-shaped shelf hangers having their central loops engaged in holes in said inwardly projecting arms of said uprights, thereby presenting upwardly facing shelf engaging hooks, and shelves having end flanges engaged in said hanger hooks, the end flanges of said shelves having lugs struck inwardly therefrom engaging said hangers so that the shelves constitute tie members for the uprights.
5. In a structure of the class described, the combination with front uprights formed of T iron disposed with their central arms inwardly, such arms having a vertical series of holes therein, shelf hangers selectively engageable with said holes, lugs secured to the inwardly projecting arms of said uprights in spaced relation to lateral arms thereof, bottom panel members disposed between said laterally projecting arms of said uprights and said lugs and having inturned flanges at their rear upper edges resting on said lugs, and a shelf having downturned flanges at its ends engaged with said hangers and a downturned flange on its front edge having an inturned portion at the bottom thereof resting on said top flange of said bottom panel.
6. In a structure of the class described, the combination with front uprights formed of T iron disposed with their central arms inwardly, shelf hangers on said uprights, lugs secured to the inwardly projecting arms of said uprights in spaced relation to lateral arms thereof, bottom panel members disposed between said laterally projecting arms of said uprights and said lugs and having inturned flanges at their upper edges resting on said lugs, and a shelf engaged with said hangers and having a downturned flange on its front edge engaging said top flange of said bottom panel.
7. In a structure of the class described, the combination of front and rear T iron uprights disposed with their central arms inwardly and having a vertical series of holes therein, a corner upright having a vertical series of holes therein disposed in alinement with the rear upright, hangers selectively engageable with said holes in said uprights, and triangular shelves having downturned flanges on their edges, their side flanges being notched at their rear ends and adjacent their front ends to engage said hangers, the side flanges having bendable lugs at their rear ends disposed below the supporting hangers on the rear upright.
8. In a structure of the class described, the combination of front and rear T iron uprights disposed with their central arms inwardly, a corner upright disposed in alinement with the rear upright, hangers on said uprights, and triangular shelves having downturned flanges on their side edges engaged with said hangers, the side flanges having lugs at their rear ends disposed below the supporting hangers on the rear upright.
9. In a structure of the class described, the combination of front and rear uprights, and a corner upright disposed in alinement with the rear upright, said uprights having hangers thereon, a curved bottom panel having inturned flanges disposed in abutting relation to the front upright and the corner upright, and a bottom shelf having downturned flanges on its edges, its front edge being rounded and its flange overlapping the upper edge of said bottom panel, the side flanges being slotted to receive the upper edge of said bottom panel.
10. In a structure of the class described, the combination of one inner and two outer uprights disposed in triangular relation and having a vertical series of holes therein, shelf hangers selectively engageable with said holes, and corner shelves engageable with said hangers and provided with lugs projecting below the hanger on the inner upright to support the shelf against tilting movement.
11. In a structure of the class described, the combination of triangularly disposed uprights having hangers thereon, a curved bottom panel disposed with its ends in abutting relation with two of said uprights, and a bottom shelf engaging said hangers and having downturned flanges on its edges disposed with its front edge in overlapping relation to the upper edge of the bottom panel, its side flanges being slotted to receive the upper edge of the bottom panel.
- In witness whereof I have hereunto set my hand.
- CHARLES H. JARVIS.
